UNITED STATES PATENT OFFICE.

HENRY JOSEPH ROUND, OF LONDON, AND GEORGE MAURICE WRIGHT, OF CHESTERFIELD, ENGLAND, ASSIGNEES, BY MESNE ASSIGNMENTS, TO RADIO CORPORATION OF AMERICA, OF NEW YORK, N. Y., A CORPORATION OF DELAWARE.

WIRELESS TELEGRAPHY.

1,403,640.

Specification of Letters Patent. Patented Jan. 17, 1922.

Application filed February 20, 1920. Serial No. 360,127.

To all whom it may concern:

Be it known that we, HENRY JOSEPH ROUND, a subject of the King of Great Britain, residing at 9 Woodberry Crescent, 5 Muswell Hill, London, England, and GEORGE MAURICE WRIGHT, a subject of the King of Great Britain, residing at Lyngrove, Cromwell Road, Chesterfield, England, have invented new and useful Improvements in 10 Wireless Telegraphy, of which the following is a specification.

In direction finding systems, such as the Bellini-Tosi, practical difficulties of operation arise owing to the necessity for very 15 accurate tuning of the aerials. This close tuning is required in order that the currents generated in the aerials may bear the correct phase relationship to each other.

According to the present invention we obviate this difficulty by constructing a Bellini direction finder so that the mutual inductance between the field coils and the exploring coil is as great as possible, and by connecting in the circuit of the exploring 20 coil a single variable condenser we are then able to use closed loop aerials which practically speaking have of themselves no definite natural period as we can obtain all the necessary tuning by varying the capacity of the 25 aforesaid condenser. We also find that by this invention any errors owing to slight inaccuracies in laying out of the aerials are rendered of less effect.

Our invention is illustrated by the accompanying drawing, in which Figure 1 is a perspective view and Figure 2 a diagram.

A B C and A D E are the two loop aerials of a Bellini direction finding system. These aerials have field coils G H and J K which 40 are arranged in the usual way but are aperiodic. The exploring coil L is arranged to move in the field coils and the whole is constructed so that the mutual inductance between L and J K and G H is as great as 45 possible. If this mutual inductance is great enough the whole system of aerials and search coil can be tuned by means of a variable condenser M in series with the coil L. By this means we dispense with the separate 50 tuning of each aerial while maintaining accuracy and efficiency.

In order to avoid any ill effects due to the electrostatic coupling between the aerials and the search coil and its associated receiver circuits we find it of great advantage to connect the mid-points of G H and J K together and to earth as shown. This has the effect of ensuring that the field coils remain definitely at earth potential. We sometimes find it advantageous to earth this point 60 through a condenser, inductance or resistance or a combination thereof.

What we claim is:—

1. The combination of two closed loop aperiodic aerials with an inductance coupled 65 to them and a variable condenser connected to the inductance.

2. The combination of two closed loop aperiodic aerials, an inductance connected to each aerial, an earth connection to the middle 70 point of each inductance, a third inductance coupled to said inductances and a variable condenser connected to the last mentioned inductance.

3. The combination of two closed loop 75 aperiodic aerials each having a field coil connected thereto, an exploring coil so situated with regard to the field coils that the mutual inductance between it and them is as great as possible and a variable condenser connected to the exploring coil.

4. The combination of two closed loop aperiodic aerials each having a field coil connected thereto, an exploring coil so situated with regard to the field coils that the 85 mutual inductance between it and them is as great as possible, a variable condenser connected to the exploring coil and an earth connection to a point between the two field coils of each loop.

5. The combination of two closed loop aperiodic aerials each having in its lowest limb an inductance, an earth connection to the middle point of each inductance, a third inductance coupled to the inductances in the 95 two loops and a variable condenser connected to this last mentioned inductance.

6. The combination of two closed loop aperiodic aerials each of which has in its lowest limb field coils, an exploring coil so 100 situated with regard to the field coils that the mutual inductance between it and them

is as great as possible and a variable condenser connected to the ends of the exploring coil.

7. The combination of two closed loop aerials each of which has in its lowest limb field coils, an exploring coil so situated with regard to the field coils that the mutual inductance between it and them is as great as possible, a variable condenser connected to

the ends of the exploring coil and an earth connection to a point between the two field coils of each loop.

In testimony that we claim the foregoing as our invention, we have signed our names this 16th day of January, 1920.

HENRY JOSEPH ROUND.
GEORGE MAURICE WRIGHT.
